UNITED STATES PATENT OFFICE.

JOHN FIELDING, OF GLOUCESTER, ENGLAND.

SUCTION GAS-GENERATOR.

No. 877,068.

Specification of Letters Patent.

Patented Jan. 21, 1908.

Application filed July 10, 1906. Serial No. 325,483.

To all whom it may concern:

Be it known that I, JOHN FIELDING, a subject of the King of Great Britain, residing at Gloucester, England, engineer, have 5 invented new and useful Improvements in Suction Gas-Generators.

The invention relates to an improved means for generating and automatically regulating the amount of steam which it is 10 found advantageous to employ in the working gas generators which work by suction.

According to my invention air together with a regulated amount of water is caused to pass radially through a heated hollow circular plate upon which the incandescent fuel rests, in such a manner that the air, together with the steam, passes into the fuel regularly and uniformly all around the base of the fire. The air, together with water in 20 a sprayed condition, enters through a central passage from which they spread radially in a thin stream which is interrupted and diverted by a number of heated bars or fins presenting a large amount of heating surface. The hollow plate may be stationary, or it may be so arranged that it can be rotated for the purpose of facilitating the discharge of the ash and clinker.

Automatic regulation of the quantity of 30 water for conversion into steam is effected in the following manner. When the engine is working to its full capacity a maximum amount of water may be used in the producer, but at light or no load it is preferable 35 to proportionately diminish the supply of water or cut it off altogether.

In this class of gas generator the supply of air necessary for combustion of the fuel enters by atmospheric pressure whenever 40 the engine draws away a charge of gas, the quantity of air being therefore in proportion to the power exerted, because no air enters the producer when by the action of the engine governor the gas inlet valve remains closed 45 during the engine's charging stroke. According to my invention I take advantage of this intermittency of the air supply for the purpose of regulating the supply of water in the following manner. I provide a branch 50 piece which admits the air to the generator, having four branches, two of these are preferably horizontal, viz., the branch admitting air, and one immediately opposite leading to the steam generating portion of the producer, a vertical inverted water jet is placed 55 about centrally of the two air branches, with

suitable means for regulating the quantity of water, which may flow in a regular stream or series of drops. Beneath the jet is arranged an outlet pipe leading preferably to 60 a water seal and the water falling from the jet passes away down this outlet pipe except at such times as the engine is taking its charge of gas. At these times the falling jet is deflected laterally by the current of air entering 65 the generator, causing the water so deflected to be carried into the generator.

Referring to the drawings, Figure 1 shows a vertical section of the lower part of a gas generator showing my improved form of 70 steam generating and air heating grate. Fig. 2 a cross section and Fig. 3 in sectional elevation the improved apparatus for regulating the supply of water in enlarged scale.

A. is the fire chamber with lining B. of fire- 75 brick contained in a metal casing C.

D. is a base piece fitted with the usual cleaning out and poking doors.

E. is the lower part of the double fire grate which in this case is made rotative, for this 80 purpose it is pivoted upon a central air inlet pipe F. and it is preferably supported upon antifriction balls G., E. is provided, when made rotative with suitable means such as toothed rim E¹ with pinion H., shaft and 85 handle J.

K. is the upper part of the double fire grate having formed upon its lower surface fins or ribs K¹, these ribs become highly heated in working, so that the water spray which enters suspended in the entering air becomes 90 converted into steam.

K² are ribs formed upon the upper surface of K. for the purpose of causing the lower part of the fire to rotate with the plate, 95 thereby producing some disturbance of the heated fuel which is beneficial at times.

L. is the air inlet pipe, M. the water supply pipe, N. the regulating valve, O. the water pipe leading to L.

P. is the pipe provided for the escape of 100 surplus water.

The construction of my improved apparatus for regulating the supply of water is shown in Figs. 1 & 3. Q. is the water jet. 105 In Fig. 1 the water is indicated as dropping from the jet Q in a vertical line and escaping away through the pipe P., there being at the time not sufficient entry of air by the pipe L. to disturb it, but in Fig. 3 it is assumed that a 110 full current of air is entering causing the water to be carried towards the generator,

where it mixes with the air and is converted into steam by contact with the heated surfaces of the double grate K.

Having described my invention what I claim is:

1. In a suction gas generator the combination of an air inlet pipe, a water inlet in the upper wall of said pipe, a water outlet opposite to the water inlet, a hollow fire grate on the mouth of the air inlet pipe, ribs between the plates of the grate, and means for facilitating the discharge of the ash and clinker, as and for the purpose specified.
- 10

2. In a suction gas generator the combination of an air inlet pipe, a water inlet in the upper wall of said pipe, a water outlet opposite to the water inlet, a hollow fire grate pivoted upon the mouth of the air inlet pipe, ribs between the plates of the grate, and means for rotating the grate, as and for the purpose specified.

JOHN FIELDING.
